CLAIM

The ornamental design for a screwdriver head, as shown and described.

DESCRIPTION

FIG. 1 is a front, right, top perspective of a screwdriver head according to my new design.

FIG. 2 is a rear, left, bottom perspective of the screwdriver head thereof.

FIG. 3 is a front view of the screwdriver head thereof.

FIG. 4 is a rear view of the screwdriver head thereof.

FIG. 5 is a left-side view of the screwdriver head thereof.

FIG. 6 is a right-side view of the screwdriver head thereof.

FIG. 7 is a top view of the screwdriver head thereof; and,

FIG. 8 is a bottom view of the screwdriver head thereof.

This design is directed to a screwdriver head. The broken lines are for illustrative purposes only and form no part of the claimed design.
